US0D1034434S

(12) **United States Design Patent** (10) Patent No.: **US D1,034,434 S**
(45) Date of Patent: ** Jul. 9, 2024

(54) **BATTERY FOR CAMERA**

(71) Applicant: **Yong Yi**, Shenzhen (CN)

(72) Inventor: **Yong Yi**, Shenzhen (CN)

(**) Term: **15 Years**

(21) Appl. No.: **29/861,162**

(22) Filed: **Nov. 28, 2022**

(51) LOC (14) Cl. **13-02**

(52) U.S. Cl.

USPC **D13/103**

(58) **Field of Classification Search**

USPC D13/103, 104, 107–110, 112, 119, 154,
D13/120, 184, 199; D16/237; D14/251,

(57) **CLAIM**

The ornamental design for a battery for camera, as shown and described.

DESCRIPTION

FIG. 1 is a top, front, right side perspective view of a battery for camera, showing my new design;

FIG. 2 is a bottom, front, right side perspective view thereof;

FIG. 3 is a bottom, rear, left side perspective view thereof;

FIG. 4 is a front view thereof;

FIG. 5 is a rear view thereof;

FIG. 6 is a left side view thereof;

FIG. 7 is a right side view thereof;

FIG. 8 is a top view thereof; and,

FIG. 9 is a bottom view thereof.

The broken lines in the drawings depict portions of the battery for camera that form no part of the claimed design.

1 Claim, 9 Drawing Sheets
